(57) **CLAIM**

The ornamental design for a handbag cradle, as shown and described.

DESCRIPTION

FIG. 1 is a perspective view of a front side of a handbag cradle supporting a handbag in accordance with a first embodiment of the present invention.

FIG. 2 is a perspective view of the front side of the cradle of FIG. 1 without the handbag.

FIG. 3 is an elevational view of the front side of the cradle of FIG. 2.

FIG. 4 is an elevational view of a back side of the cradle of FIG. 2.

FIG. 5 is an elevational view of a first lateral side of the cradle of FIG. 2, which is a mirror image of an opposing second lateral side of the cradle of FIG. 2.

FIG. 6 is a plan view of the cradle of FIG. 2; and, FIG. 7 is a view of a bottom side of the cradle of FIG. 2. The broken line portions of the disclosure are for illustrative purposes only and form no part of the claimed design.

1 Claim, 6 Drawing Sheets
